PLANING ATTACHMENT FOR JOINTERS

Eric Lee Carey, Ottawa, Ontario, Canada

Application May 4, 1951, Serial No. 224,577

5 Claims. (Cl. 144—117)

1

This invention relates to woodworking machines.

In most small woodworking shops, and particularly in home workshops, the need for both jointing and planing operations frequently arises. However, since the cost of power-driven planers and jointers is high, many such workshops are equipped with jointers only and have no facilities for power planing.

It is an object of the present invention to provide a simple and inexpensive attachment for a jointer, such attachment being subject to convenient mounting on an existing jointer and being capable of rendering such jointer suitable for performing planing operations in a highly satisfactory manner.

The invention will be described with reference to the accompanying drawings, in which,

Fig. 1 is a side elevation of a jointer equipped with the attachment of the present invention,

Fig. 2 is an enlarged sectional side elevation of a portion of the attachment,

Fig. 3 is a plan view of the attachment,

Fig. 4 is an enlarged sectional elevation of an alternative form of supporting means for the attachment, and

Fig. 5 (sheet 1) is an enlarged sectional view of an alternative form of another supporting means for the attachment.

In the drawing, the jointer shown is of standard construction and includes a base 1, on which are slidably mounted the two bed sections 2 and 3, each adjustable for height by means of a respective hand wheel 4. The cutting head is diagrammatically indicated at 5.

The attachment of the present invention comprises a bed plate 6 mounted on posts 7 (preferably four in number) which are arranged to be anchored in bed section 2 of the jointer and which are adapted to support the plate in a horizontal plane and in elevated spaced relation to the surface of such section by the posts. The bed plate is preferably formed of metal of sufficient thickness to impart rigidity thereto. A one-quarter inch metal plate has been found satisfactory for the purpose. The plate may vary in size within wide limits. However, a plate approximately 24 inches long by 12 inches wide provides satisfactory operation for general use. One end of the plate is adapted to extend in elevated spaced relation over the head 5 and adjacent portion of the other bed section 3. Suspended from the latter end of the plate, as by a pair of rods 8, is a pressure plate 9 in generally parallel relation to plate 6. The plate 9 is of

2

approximately the same width as plate 6 and may be approximately nine inches long.

It will be observed that the major portion of the plate 9 (for instance, about six inches thereof) underlies bed plate 6, the inner edge thereof being arranged to lie in proximity to the cutting head 5. Such inner edge is preferably provided with a depending reversely inclined flange 10, which constitutes a deflecting apron for shavings and the like. The outer end portion of pressure plate 9 extends preferably somewhat beyond the adjacent end of bed plate 6. The edge of such outer end is preferably downwardly inclined to provide a lip 11, and a complementary lip 12 is formed on the adjacent edge of bed plate 6 to facilitate insertion of a board (as indicated at 13) therebetween.

The pressure plate 9 is arranged to normally lie at a distance from bed plate 6 approximately equal to the spacing of bed plate 6 from bed section 2. However, on insertion of a board between such plates of a thickness greater than said distance, the pressure plate 9 is adapted to move downwardly sufficiently to permit such insertion and to exert a pressure on the lower face of the board to hold the upper face of the board under pressure against the lower surface of bed plate 6. To this end, a bushing 14 is provided on each rod 8, the lower end of the bushing engaging the plate 9 and the upper end being engaged by a spring 15 retained in place by a nut 16 threaded onto the upper end of rod 8. It will be apparent that the nut 16 may be adjusted to vary the pressure applied through the spring by the plate 9.

In order to accommodate various thicknesses of boards, it is advisable that means be provided to adjust the distance between the bed plate 6 and bed section 2 and cutting head 5 and also to correspondingly adjust the distance between bed plate 6 and pressure plate 9. Such means may comprise a sprocket 17 threadedly mounted on each post 7. Each sprocket has a recessed hub portion 18 which extends through the bed plate and is removably locked therein by means of a washer 19 and spring ring 20. The under surface of the bed plate may be suitably countersunk as indicated at 21 to receive the washer and spring ring. Sprockets 17 are likewise threadedly mounted on bushings 14 of the rods 8. A sprocket chain 22 is mounted on the sprockets 17, idler rollers or the like 23 and 24 being preferably provided on the bed plate to engage the chain between rods 8 and adjacent posts 7 to provide more effective driving engagement of the chain with the sprockets. Roller 23 is preferably car-

ried by a slotted arm 25 mounted on a support 28 carried by the bed plate. The position of the arm 25 may be adjusted by means of bolt 26 and wing nut 27 to impart tightening action to the chain. Bushings 14 are connected by a rod 14' to prevent turning movement of the bushings. One of the sprockets 17 (as shown, that on post 7 adjacent roller 23) is provided with a crank arm 29 which may be manually revolved to rotate all sprockets 17 simultaneously. It will be apparent that rotation of the sprockets in one direction will cause the bed plate to move upwardly and the pressure plate to move downwardly due to the threaded connection with the posts 7 in the one case and the threaded connection with the bushings 14 in the other case, the diameter of the posts 7 and bushings 14 and the size of threads thereon being so chosen as to provide equivalent movement of each plate.

Figure 4 illustrates an alternative sprocket mounting for the bushing 14. As shown, a sprocket 30 has threaded engagement with the bushing which extends through an opening 31 in the bed plate 6. The hub 32 of the sprocket is seated on the bed plate and is supported by a suitable bearing 33 mounted on the plate. A bracket 34 retains the sprocket in position while permitting rotation thereof.

Figure 5 illustrates an alternative sprocket mounting for the post 1. As shown, a sprocket 35 has screw threaded engagement with a bushing 36 which extends through the bed plate 6 and has a retaining shoulder 37 engaging the under surface of the plate. The sprocket is fixed in position on the bushing by means of a set screw 38. The bushing is threadedly mounted on the post 1.

In operation, the plates 6 and 9 are adjusted to any desired position to plane a board of specific thickness, the board being effectively held against the bed plate 6 by the pressure plate 9 to provide a satisfactory planing operation by the cutting head 5. Moreover, such planing operation may be carried out in a very rapid manner.

I claim:

1. A planing attachment for a jointer having a pair of bed sections and a cutting head comprising a bed plate, a plurality of supporting posts for the bed plate, the lower ends of said posts being arranged to be anchored in one of said bed sections, said posts being adapted to support the bed plate in spaced parallel relation to said bed sections with one end portion of the bed plate in overlying relation to the cutting head and other bed section, a pressure plate, rods suspending said pressure plate from said end portion of the bed plate, springs carried by the rods and urging the pressure plate towards the bed plate, rigid spacing means between said plates to normally hold said pressure plate in a position in spaced, parallel, underlying relation to the bed plate and arranged to overlie said other bed section, said rods being slidably mounted in the bed plate to permit movement of the pressure plate out of said position away from the bed plate, and means for simultaneously adjusting said position of the pressure plate and the position of the bed plate with respect to the posts.

2. A planing attachment as defined in claim 1, 70 the edge of said end portion of the bed plate and

the adjacent edge of said pressure plate each having an outwardly flared lip to facilitate the insertion of a board therebetween.

3. A planing attachment as defined in claim 1, 5 the inner edge of said pressure plate having a downwardly extending flange constituting a shavings deflecting apron.

4. A planing attachment for a jointer comprising a rectangular bed plate having a work-engaging bottom surface, said bottom surface lying in an uninterrupted plane and extending longitudinally from end to end of the bed plate, a plurality of supporting posts mounted in the bed plate laterally of said work engaging surface, a rectangular pressure plate carried by the bed plate independently of said supporting posts and having a work-engaging upper surface in spaced, parallel, relation to said bottom surface and in directly opposed relation to at least a portion of said bottom surface, said upper surface lying in an uninterrupted plane and extending longitudinally from end to end of said pressure plate, means holding said pressure plate in a position at a predetermined distance from the bed plate and restraining movement of the pressure plate towards the bed plate, said means permitting movement of the pressure plate away from the bed plate, resilient means carried by said holding means and urging the pressure plate towards the bed plate to hold work between said work-engaging surfaces, and means for varying said position of the pressure plate and for varying the position of the bed plate with respect to the posts.

35 5. A planing attachment for a jointer comprising a rectangular bed plate having a work-engaging bottom surface, said bottom surface lying in an uninterrupted plane and extending longitudinally from end to end of the bed plate, 40 a plurality of supporting posts mounted in the bed plate laterally of said work-engaging surface, a rectangular pressure plate having a work-engaging upper surface, said upper surface lying in an uninterrupted plane and extending from end to end of said pressure plate, rods suspending the pressure plate from one end portion of the bed plate with said upper surface in spaced, parallel relation to said bottom surface and in directly opposed relation to at least a portion of 45 said bottom surface, springs urging the pressure plate towards the bed plate to hold work between said work-engaging surfaces, rigid spacing means between said plates to normally hold said pressure plate in a position at a predetermined distance from the bed plate, said rods being slidably mounted in the bed plate to permit movement of the pressure plate out of said position away from the bed plate, and means for simultaneously adjusting said position of the pressure plate and the position of the bed plate with respect to the posts.
